UNITED STATES PATENT OFFICE.

BENJAMIN F. COX, OF MERCEDES, TEXAS.

GAME-RETAINING GARMENT.

1,307,244.

Specification of Letters Patent. Patented June 17, 1919.

Application filed November 30, 1917. Serial No. 204,630.

To all whom it may concern:

Be it known that I, BENJAMIN F. Cox, a citizen of the United States, residing at Mercedes, in the county of Hidalgo and State 5 of Texas, have invented certain new and useful Improvements in Game-Retaining Garments, of which the following is a specification.

This invention relates to apparel and the 10 invention has more especial reference to an improved sportsman's garment.

The invention has for its dominant object to provide a novel garment in form of a coat having a game receiving pocket therein 15 for retaining the game shot, which, as it becomes necessary, can be easily and thoroughly cleaned, thus rendering the garment sanitary and adding materially to the durability of the same.

20 Another and equally important object of the invention is to provide a garment having shell retaining pockets formed therein and so arranged as to permit ready access thereto.

25 It is also an object of the invention to provide a coat of the character mentioned having the sleeves thereof detachably mounted in order that the same can be readily removed for washing or when it is desired 30 to use the garment as a vest.

Yet another object of the invention is to provide the garment with a novel bosom, the same being detachably engaged with the neck portion of the garment, whereby an 35 effectual shield for the chest of the wearer will be provided.

The improvements in the details and arrangement of parts will be apparent from an inspection of the accompanying drawings, 40 in connection with the specific description hereinafter contained, and wherein the preferred embodiment of the invention is disclosed for the purpose of imparting a full understanding of the same.

45 In the drawings:—

Figure 1 is a plan of the improved garment,

Fig. 2 is a longitudinal section therethrough,

50 Fig. 3 is a vertical section through the same,

Fig. 4 is a front elevation thereof, and

Fig. 5 is a detail elevation of the bosom attachment.

55 Having more particular reference to the

drawings and in connection with which like reference characters will designate corresponding parts throughout the several views of the drawings, 1 represents the body of the garment, the same being formed in the 60 shape of the conventional design of vest; having arm receiving openings therein and means, hereinafter described for fastening the garment about the body of a user.

It is to be noted, that the lower portion 65 of the garment is curved as at 2 in order that the same will properly conform to the body of a person when arranged thereabout.

Stitched to the lower portion of the body 1 is a transversely disposed piece of fabric 70 3 having series of eyelets 4 arranged adjacent certain of the edges thereof, it being noted in this connection, that the upper portion only of the said strip of fabric is stitched to the body portion 1. Suitable 75 openings are left in the opposite ends of the pocket formed by the arrangement of the strip of fabric 3 and as will be appreciated, will permit the placing or removing of game therein by the user. Other openings or slits 5 are formed in the body portion 1 and communicate with the pocket formed in the garment, thereby affording other means of access for the same.

80 A series of eyelets 6 are arranged in the 85 lower portion of the body 1 corresponding to the eyelets 4 arranged in the fabric strip 3 and are adapted to receive laces 7 therethrough, whereby the lower portion of the fabric strip may be detachably connected to 90 the body 1, thus, completing the pocket.

Shell or cartridge receiving pockets 8 are formed in the lower portion of the body 1 at points convenient to the hands of a user and are normally closed by flaps 9 arranged 95 thereover.

Due to the fact that the eyelets 4 and 6 extend for a distance along the opposite sides of the body of the garment, it will be readily understood that the same may be held about 100 the body of a user, by means of the laces 7.

Engaged with the marginal portion of the neck portion of the garment are a plurality of fasteners, which fasteners are adapted to be engaged by complementary fasteners arranged adjacent the marginal edge of a neck or bosom portion 10; the said bosom portion having the front thereof open and adapted to be connected by buttons 11 or other suitable fastening means. Obviously, by at- 105 110

taching the neck or bosom portion 10 to the garment, the same will be converted into an efficient coat.

5 Series of other fasteners are arranged adjacent the arm holes of the garment and are adapted to be engaged with complementary fasteners carried on the adjacent ends of sleeves 12, it being noted that the said sleeves are provided with flaps upon the 10 ends thereof capable of fully covering the shoulders of the body portion of the garment.

15 By providing the garment with detachable sleeves and the detachable bosom or neck portion, it will be readily understood that the same may be instantly converted into a coat or if desired, worn as a vest. Thus, the user is afforded two garments.

20 When using the improved garment, it will be readily understood that the pocket formed by the arranging of the strip of fabric 3 may be easily and readily cleaned as it becomes necessary, thereby rendering the garment sanitary and adding materially to 25 the durability thereof by preventing the accumulation of dirt and other matter therein.

Manifestly, the construction shown is capable of considerable modification and such modification as is within the scope of my 30 claims, I consider within the spirit of my invention.

I claim:—

1. A garment of the character described 25 having a transversely disposed strip of fabric stitched at one edge to the intermediate portion thereof, means engageable with the free portions of said strip and the adjacent

portions of the garment for temporarily closing the same, said garment having slits formed therein communicating with the 40 pocket formed by the arrangement of said strip of fabric thereacross.

2. A garment of the character described including a body, a strip of fabric stitched transverse at one side to the intermediate 45 portion of the body, eyelets arranged in the free portions of said strip of fabric and the body portion, means receivable through said eyelets for detachably connecting the strip to the body portion, said body portion having 50 openings formed therein communicating with the pocket formed by the arrangement of said strip of fabric.

3. A garment of the character described including a body, a transversely disposed 55 strip of fabric stitched adjacent one edge thereof to the intermediate portion of said body, said strip of fabric being of a length corresponding to the width of the body, removable fastening means engaged with the 60 lower portions of said strip of fabric and the body and with portions of the ends of said strip and the adjacent portions of the sides of the body whereby to form a pocket in the lower portion of the garment extending 65 entirely across the body and having hand openings in its opposite ends, the intermediate portion of the body having vertical hand receiving openings therein to provide further means of access to said pockets. 70

In testimony whereof, I affix my signature hereto.

BENJAMIN F. COX.
